UNITED STATES PATENT OFFICE.

MARIAN CURRY TEBBETTS AND ELIZABETH PORTER TEBBETTS, OF PITTSBURGH, PENNSYLVANIA.

DESIGN FOR A DOLL.

Application filed February 19, 1923. Serial No. 5,199. Term of patent 7 years.

To all whom it may concern:

Be it known that we, MARIAN CURRY and ELIZABETH PORTER TEBBETTS, citizens of the United States, residing at Pittsburgh, in the county of Allegheny and State of Pennsylvania, have invented a new, original, and ornamental Design for Doll, of which the following is a specification, reference being had to the accompanying drawing, forming part thereof.

We claim:

The ornamental design for a doll, as shown.

MARIAN CURRY TEBBETTS.
ELIZABETH PORTER TEBBETTS.
